(57) **CLAIM**

The ornamental design for a display screen or portion thereof with animated graphical user interface, as shown and described.

DESCRIPTION

FIG. 1 is a first image in a sequence shown on the display screen or portion thereof with animated graphical user interface;

FIG. 2 is a second image in the sequence shown thereon; and,

FIG. 3 is a third image in the sequence shown thereon. The broken lines showing a display screen or portion thereof and portions of the graphical user interface form no part of the claimed design.

The appearance of the transitional image sequentially transitions between the images shown thereon. The process or period in which one image transitions to another image forms no part of the claimed design.
